Des. 223,903
Patented June 20, 1972

223,903

BURIAL CASKET

Fred Herricht, Bechtelsville, Pa., assignor to Boyertown
Burial Casket Company, Boyertown, Pa.

Filed Oct. 21, 1970, Ser. No. 25,587

Term of patent 14 years

Int. Cl. D31

U.S. Cl. D19—1

Fig. 3

Fig. 6

Fig. 4
Fig. 5FIG. 1 is a side, top and end perspective view of a burial casket, showing my new design;

FIG. 2 is a top plan view;

FIG. 3 is a side elevational view, the opposite side being substantially a mirror image thereof;

FIG. 4 is an end elevational view, the opposite end being substantially a mirror image thereof;

FIG. 5 is a reduced scale bottom plan view; and

FIG. 6 is an enlarged scale fragmentary cross-sectional view taken along line 6-6 in FIG. 3.

I claim:

The ornamental design for a burial casket, as shown and described.
